United States Patent

Des. 239,529

Patented Apr. 13, 1976

239,529

DECORATIVE ARCHITECTURAL PANEL

Emory L. Mead, Oak Park, Ill., assignor to
Design Works, Inc., Oak Brook, Ill.

Filed Nov. 29, 1974, Ser. No. 527,966

Term of patent 14 years

Int. Cl. D25—01

U.S. Cl. D18—2 B

Fig. 1.

Fig. 2.

Fig. 3.

FIG. 1 is a front elevational view of a decorative architectural panel showing my new design;

FIG. 2 is a rear elevational view of the decorative architectural panel illustrated in FIG. 1; and

FIG. 3 is a vertical sectional view taken substantially along the line 3—3 of FIG. 2 and looking in the direction of the arrows thereon.

I claim:

The ornamental design for a decorative architectural panel, substantially as shown.
